ILLUMINATED DECORATIVE DEVICE

Elmer J. Graf, Roselle Park, N. J., assignor to
 G. B. G. Corporation, Newark, N. J., a corpora-
 tion of New Jersey

Application February 2, 1934, Serial No. 709,459

14 Claims. (CL. 240—10)

This invention relates to ornamental devices which may be illuminated and especially adapted for use as decorations on Christmas trees.

It has been the usual practice in the past to trim Christmas trees with festoons made up of lamp sockets carrying bulbs connected in series, each series being connected to a suitable socket associated with a standard electric light circuit, such circuits usually having a pressure of 110 volts. In the arrangement above described, the decorative effects have usually been determined by the shape and color of the bulbs themselves. Where the trees are lighted in the manner described, the bulbs are very apt to become broken, and when any one series is broken, the entire group is rendered inoperative.

I have heretofore designed an ornamental illuminated unit made up of stamped or formed material, the stampings being provided with sockets for carrying baseless light bulbs which for each unit are all connected in series. By making the frame of the unit of thin metal, the entire unit is light, yet very strong. However, I do not wish to be limited to the use of metal, as some other heat-resisting material may be used in constructing the unit.

My present invention has for one of its objects a construction somewhat similar to that just referred to, but in which the cost is materially reduced, while at the same time practically all of the ornamental effects of my previous design are retained.

My present invention will be best understood by reference to the attached drawing, wherein:

Figure 1 is a plan view of one form of my new construction.

Figure 2 is a view of the back of Figure 1 with certain of the parts removed.

Figure 3 is a side elevation of the device, with certain of the parts removed.

Figure 4 is a section on the line 4—4 of Figure 1.

Figure 5 is an end view of the terminal end of the lamp showing the special means for fastening the lamp in the holder or casing.

Figure 6 is a plan view of a modified form of the device shown in Figure 1.

Figure 7 is a side elevation of Figure 6.

Figure 8 is a view of the single lamp bulb used in my present design, together with the means for supporting the bulb.

Figure 9 is a quarter-section and elevational view, on an enlarged scale, of a light-dispersing means which is shown in Figure 1.

55 In the various views, wherein like numbers

refer to corresponding parts, 1 and 2 represent the front and back parts of a casing. These parts are stamped out of sheet material, preferably tin, although a suitable heat-resisting material other than metal can be used; in fact, one part may be of metal and the other non-metallic, or both non-metallic, and each of the parts 1 and 2 has complementary arms 3 arcuately formed and extending radially from the central portion or body of the casing. The two parts 1 and 2 are fastened together in any satisfactory manner, preferably by a plurality of lugs 4, which are shown as being on part 1, and which are bent over the body portion 2 as clearly shown in Figure 2.

The central portion of the part 2 has an orifice 5 through which a single lamp bulb 6 may be passed. Securely fastened at the junction of the bulb and the stem of the lamp, as by a suitable heat-resisting cement, is an insulator 7 which is adapted to lie over and cover the orifice 5 in the back part 2 of the casing. As shown in Figure 8, the support insulator 7 is spaced a considerable distance from the bulb 6, and in some cases, so the heat therefrom will not deleterious- 25 ly affect the insulator, a disc 25 of insulating material is forced over the stem 27 before the holder 7 is put in place, thereby forming a space 26 for a quantity of the cement.

Fingers 8 are thrown up from the body portion of the member 2 adjacent the periphery of the opening 5, and when the lamp bulb and its insulating support 7 have been placed in position, the fingers 8 are bent downwardly over the edge of the insulator, thereby locking the bulb securely in position to the back casing member 2. When both the members 1 and 2 are not made of metal, other locking means may be used.

The front casing member 1 preferably has its central portion 9 formed or punched outwardly, 40 and preferably this outwardly formed portion 9 is decorative in design as shown by the star-shaped figure 10 of Figure 1. In this star-shaped figure are a plurality of openings 11 which are shown triangularly in shape and which serve the 45 purpose of allowing light from the bulb 6 to come through this central portion and at the same time provide ventilation for the heat generated by the lamp bulb.

As shown in Figure 1, the arms formed by the 50 complementary portions 3 carry light-dispersing members 12 which are in the shape of polygonally formed pyramids, the faces of which are broken up into surfaces triangularly arranged in diminishing areas toward the apex as shown in 55

Figure 9, where 28 and 29 are the triangularly arranged faces, and I wish it to be understood that I claim only the specific form of glass or crystal shown.

- 5 Each of the members 12 is provided with a shank 13 extending into the arms 3 and held therein in any satisfactory manner as by fingers 14 which are bent over the base faces of the members 12. One of the fingers 14 may be provided with a hole 15 for suspending the device by means of a wire passed through the hole 15. As an alternative, the insulator 7 may have a projecting portion 16 with a hole 17 therein for suspending the device.
- 15 The portion 18 of the casing opposite each of the arms 3 is arcuately formed as shown more particularly in Figure 4, so as to act as a reflector of the light rays, thereby assisting the bulb in sending its light rays out through the arms and 20 crystal dispersing members 12.

To further cheapen the construction of the device, I have found that very good results may be obtained by the construction shown in Figures 6 and 7, wherein an extension 19 may be provided on that part of the arm forming part of the back plate 2. The extensions 19 may be made triangular in shape as shown in Figure 6 to simulate the plan view of the pyramid-shaped devices 12 of Figure 1. Preferably the upper 30 end 20 of each projection 19 is bent slightly inwardly and the edges 21 may also be curved toward each other, so that light rays coming out through the arms will be reflected from the projections 19, it being understood that the extended portions 19 are treated or formed to present reflecting surfaces to light rays.

In Figure 6 it will be seen that the central ornamental device is formed by punching slots 22 therein, leaving small supporting sections 23 to retain the ornamental device on the casing member 1. Thus the slots 22 act to allow the light to come therethrough as well as to emit heat from the single lamp bulb used in the structure.

45 To further enhance the ornamental effect of the device, the body portion and the arms 3, both on the front and back, may be covered, as indicated by the partially stippled surface 24, with a mixture of a binding material such as silicate 50 of soda and finely ground up glass of various colors, thereby giving a scintillating effect to the light rays emanating from the device, as well as those striking it from extraneous sources. It may be noted in passing that the single lamp 55 bulb 6 used in this device is adapted to be operated direct from a 110-volt circuit, thereby making each unit independent of the other, although if desired, several of the units may be connected in series by using a lamp adapted to be operated 60 on a voltage equal to the supply voltage divided by the number of bulbs connected in series.

To still further enhance the ornamental effect, the bulbs themselves may be of different colored glass to give the different color effects now obtained by the differently colored bulbs as has been mentioned.

What I claim is:

1. A unitary decorative device including a plural-part formed casing with means for fastening the parts together and having complementary integral tubular arms extending radially from the central portion of the casing, light-transmitting members comprising polygonally formed pyramids of glass or the like, the faces 70 of which are broken up into surfaces triangularly

arranged in diminishing areas toward the pyramid, said pyramids having shanks extending into said arms with means for holding said members in said arms, and means located in the central portion for illuminating all of said members. 5

2. A unitary decorative device including a plural-part formed casing with means for fastening the parts together and having complementary integral tubular arms extending radially from the central portion of the casing, light-transmitting members comprising polygonally formed pyramids of glass or the like, the faces of which are broken up into surfaces triangularly arranged in diminishing areas toward the pyramid, said pyramids having shanks extending into said arms with means for holding said members in said arms, and a single lamp bulb located in the central portion for illuminating all of said members. 15

20 3. A unitary decorative device including a plural-part formed casing with means for fastening the parts together and having complementary integral tubular arms extending radially from the central portion of the casing, light-transmitting members comprising polygonally formed pyramids of glass or the like, the faces of which are broken up into surfaces triangularly arranged in diminishing areas toward the pyramid, said pyramids having shanks extending into said arms 30 with means for holding said members in said arms, said central portion of at least one of said casing parts being bulged outwardly and a single lamp bulb located in the central portion for illuminating all of said members. 35

4. A unitary decorative device including a plural-part formed casing with means for fastening the parts together and having complementary integral tubular arms extending radially from the central portion of the casing, light-transmitting members comprising polygonally formed pyramids of glass or the like, the faces of which are broken up into surfaces triangularly arranged in diminishing areas toward the pyramid, said pyramids having shanks extending into said arms with means for holding said members in said arms, and a single lamp bulb located in the central portion for illuminating all of said members, said lamp bulb having an insulator permanently attached thereto and the insulator fitting over an orifice in one of said casing parts with means for fastening said insulator to said casing parts. 40

45 5. A unitary decorative device including a plural-part formed casing with means for fastening the parts together and having complementary integral tubular arms extending radially from the central portion of the casing, light-transmitting members comprising polygonally formed pyramids of glass or the like, the faces of which are broken up into surfaces triangularly arranged in diminishing areas toward the pyramid, said pyramids having shanks extending into said arms with means for holding said members in said arms, and a single lamp bulb located 50 in the central portion for illuminating all of said members, said lamp bulb having an insulator attached thereto and the insulator fitting over an orifice in one of said casing parts with means for fastening said insulator to said casing parts, 55 said insulator being arcuately spaced away from the filament portion of the bulb and having an ear for suspending the device. 60

6. A unitary decorative device including a plural-part formed casing with means for fasten- 75

ing the parts together and having complementary tubular arms extending radially from the central portion of the casing, light-transmitting members comprising polygonally formed pyramids of glass or the like, the faces of which are broken up into surfaces triangularly arranged in diminishing areas toward the pyramid, said pyramids having shanks extending into said arms with means for holding said members in 5 said arms, the interior of the central portion of the casing opposite said sockets being curved to form reflecting surfaces, and a single lamp bulb located in the central portion for illuminating all of said members.

15. 7. A unitary decorative device including a formed casing having cooperative locking parts and also having integral tubular arms extending radially from the casing, a lamp bulb located at the central portion of the casing so 20 as to send light rays through said tubular arms, and means located at the outer extremity of said arms for dispersing the light coming through said arms, said means comprising polygonally formed pyramids of glass or the like, the faces 25 of which are broken up into surfaces triangularly arranged in diminishing areas toward the pyramid.

8. A unitary decorative device including a formed casing having cooperative locking parts 30 and integral tubular arms extending radially from the casing, a lamp bulb located at the central portion of the casing so as to send light rays through said arms, and means comprising an extension of a part of each of said arms for dispersing the light coming through said arms, said 35 extensions being formed and treated so they will distribute light coming through the arms and impinging thereon.

9. A unitary decorative device for the purpose described including a casing having a lamp bulb located substantially at the central portion of the casing, and having the stem of the bulb extending from the casing, whereby the unit may be screwed into a socket said casing having 40 openings around its periphery through which light rays from said bulb may pass, and light-dispersing member portions extending beyond the opening at one side thereof so formed as to disperse the light coming through said openings.

45. 10. In a device of the character described including, a casing having an opening through which the bulb portion of a lamp may be passed, and light-dispersing means carried by the casing, a single lamp for the source of light and means 50 for holding the lamp within the casing with the stem of the lamp projecting outwardly away from

the casing, said means comprising insulating means securely and permanently anchored to the lamp and also fastened to the casing, whereby a complete unitary structure is formed for direct attachment to a socket. 5

11. In a device of the character described including, a casing having an opening through which the bulb portion of a lamp may be passed and light-dispersing means carried by the casing, a single lamp for the source of light and 10 means for holding the lamp within the casing with the stem of the lamp projecting outwardly away from the casing, said means comprising an insulator securely and permanently anchored to the stem of the lamp and curving away from the 15 bulb into a flange fitting over the opening in the casing and fastened thereto, whereby a complete unitary structure is formed for direct attachment to a socket.

12. For a device of the character described, 20 including a casing and a plurality of light-dispersing means carried by the casing and positioned at arcuately spaced points around the casing; an illuminating unit including a lamp structure comprising; a bulb, a metallic stem and separate insulating means permanently anchored to the lamp structure; said insulating means adapted to serve as the means for mounting the lamp within the casing so the stem of the lamp projects 25 away from the casing for the purpose described. 30

13. In a device of the character described including, a casing having a plurality of arms extending a substantial distance from the casing, light-dispersing members carried by said arms, a single lamp for the source of light having its 35 bulb positioned within the casing and having its stem projecting outwardly through an opening in the casing for attaching the entire device to a socket, the portion of the casing surrounding the opening through which the stem projects being 40 of insulating material.

14. A unitary decorative device especially adapted for Christmas tree use consisting of an illuminating unit including a lamp structure comprising; a bulb, a metallic stem, an insulator permanently anchored to the lamp structure with the stem extending away from the insulator for the purpose described, enclosure means for the bulb including said insulator, the front portion of said enclosure means allowing light to be dispersed therefrom, and a plurality of light-dispersing members carried by the enclosure means and positioned at arcuately spaced points around the enclosure so as to be illuminated by said bulb when current is applied thereto. 50 55

ELMIE R. GRAF.
